UNITED STATES PATENT OFFICE.

FRANK DELLA TORRE AND DANIEL B. BANKS, OF BALTIMORE, MARYLAND.

ALINING, SECURING, AND BONDING OF RAIL ENDS.

SPECIFICATION forming part of Letters Patent No. 700,994, dated May 27, 1902.

Application filed February 15, 1901. Renewed October 24, 1901. Serial No. 79,877. (No model.)

To all whom it may concern:

Be it known that we, FRANK DELLA TORRE and DANIEL B. BANKS, citizens of the United States, and residents of Baltimore, State of Maryland, have invented certain new and useful Improvements in Alining, Securing, and Bonding of Rail Ends; and we do hereby declare the following to be a full, clear, and exact description of the same, reference being had to the accompanying drawings, forming a part of this specification, and to the letters of reference marked thereon.

Our improvements relate to an improved process of alining, securing, and bonding the ends of railroad-rails; and the objects of our improvements are, first, to bring the ends of railroad-rails which may have become out of alinement caused by wear or otherwise to a true wheel-surface; second, to secure and hold the ends of railroad-rails with a near approach to the rigidity and flexibility of the continuous part of the rail, and, third, to effectually bond railroad-rails to insure electrical conductivity of the rail.

The above objects have in view the formation of such joints as will render the rails practically continuous and without that weakness, lack of rigidity, and impairment of wearing qualities at the joints so characteristic of prior efforts in this direction.

So far as we are aware there has been no successful solution of the problem of joining rails which have already become worn or battered at the ends without either first restoring said ends to their original shape by suitable mechanical appliances and then applying a joint thereto or by entirely cutting off and removing the distorted ends, thereby shortening the rails, either of which processes is almost as expensive and as difficult to carry out as the relaying of the track.

With the above-mentioned objects in view and in order to provide a practical process for rigidly connecting the adjacent ends of rails *in situ*, which will overcome the difficulties and defects incident to the former efforts to accomplish this end, we now unite the adjacent ends of the rails and bring the wheel-surface to a fixed or datum line by a process which may be briefly described as follows:

Assuming that the process is to be used on a track which has been in use and the rails

somewhat distorted, the adjacent ends of the rails are first exposed by a suitable excavation around the ends, the fish-plates are removed, and the ends of the rails subjected to a more or less thorough cleaning, the thoroughness of which, however, is not of particular importance so far as the present invention is concerned. Suitable clamps of approximately the shape of the top and bottom of the rails are then applied and rigidly connected, thus forming a mold in the required alinement. At this point it will be noted that should the rail ends be battered down a space will be left between the top clamp and the rail ends, the bottom surface of said top clamp being in the true alinement required. The stages of the process may proceed simultaneously one with the other or either of said stages may precede the other. We do not limit ourselves to the order of procedure. One stage of the process is to force the rail ends into said clamps after they have been placed in position, as above described. This is done by expanding or stretching the web of the rail ends. There are various methods of accomplishing this result, and we do not wish to limit ourselves to any particular method. Another stage of the process is the securing of the rail ends together by means of the welding together of chocks placed on the opposite sides of the webs thereof. Another stage of the process is the more or less complete welding of chocks placed against the webs of the rail ends to said webs, thus forming a good electrical conductor.

We will first describe what we consider the preferable apparatus for operating the above process and also one which performs the various stages almost simultaneously and after that modified forms.

Chocks, preferably of wrought-iron and heated to a welding heat, are applied to opposite sides of the web of the rail and between the head and bottom flange, so as to bridge the joint between the two rails, after which sufficient pressure is applied to opposite faces of said chocks, thereby causing said chocks to spread vertically and toward each other through openings in or near the ends of the rail. If no openings were in said rail, suitable openings are formed therein. This pressure has the effect, first, of welding the

chocks together through the openings, and, secondly, by the compression of the rail-web, which has become heated by contact with the hot chocks and the vertical pressure of the 5 plastic chocks, causes the ends of said rails to spread vertically and completely fill the space between the previously-applied clamps, or, in other words, the surface of the rail-head is brought up against the under face of 10 the clamp or mold practically at all points within the field above the chocks. The pressure is maintained a sufficient time for the parts to set in this position when the pressure is relieved, and the joint is completed with- 15 out the necessity of grinding or dressing the head of the rail, as has heretofore been found necessary.

Apparatus for carrying this invention into practice it is obvious may be of many different forms, and we have not deemed it necessary to illustrate in the accompanying drawings more than a simple form of such apparatus—namely, the clamps for holding the rails in alinement and providing a “mold,” 20 so to speak, for the top and bottom of the rail ends when the expanding of the same takes place, together with a press of such a character that the pressure necessary in carrying out the process may be effectually and conveniently applied to the chocks and rail ends.

In the accompanying drawings, Figure 1 is a side elevation of a welding-press, showing a rail in section with welding chocks and clamps thereon. Fig. 2 is a view of the same, taken 35 in elevation at right angles to Fig. 1. Fig. 3 shows a modified method of rail expansion where heated chocks are used, but not heated to the welding temperature. These sufficiently heat the web, so that it may be worked 40 and the rail expanded, as above described, after which the rails may be secured as suggested by this process or by other means. Fig. 4 shows another way of accomplishing 45 the same result. Here the necessary heat is applied to the web of the rail by means such as flame, fire, or otherwise. Then the press is brought to bear directly on the web, causing the same to expand.

Like letters of reference in the several figures indicate the same parts.

In said drawings the letters A A' indicate a pair of very heavy press-jaws pivoted together on a center at B and having upwardly-extending handles or operating portions a a'. The faces of the jaws A A' are provided with dies or anvil-faces C C', respectively, preferably held in place by bolts c c', so as to be readily removable for the substitution of new or different-shaped dies to correspond to the 55 work to be done. The upper ends of the jaws or their upward extensions a a' have interposed between them, preferably directly, a ram of a hydrostatic press, through which the power is derived for securing the pressure before referred to. In the preferred construction the extension a' at its upper end is formed 60 with or into a cylinder D, into which hydraulic

pressure may be transmitted by means of a pipe or conduit d, and working in this cylinder D is a piston or ram having a push or connecting-rod D' extending across and taking a bearing upon the extension a of the jaw A. In addition to the hydrostatic-press connections the said extensions a a' are connected together by toggle-links E, to the central joint 75 e of which a hanger or support, such as F, may be attached.

In order to position the dies properly with relation to the chocks and rails, the jaws are provided, preferably, with a gage or gages 80 which will rest upon the upper surface of the rails or the clamps applied thereto, and this gage or gages is or are preferably such that it or they may be removed and other gages substituted for different kinds of work—as, 85 for instance, where wide or narrow rails are to be operated upon. In the preferred construction two gages are employed, and they consist of two depending legs or feet G, pivotally suspended from the centers B and hanging down in position to constitute a rest for the press.

The rail ends H are suitably perforated at h near their ends, the perforations extending through the webs of the rails, and to the top 95 and bottom of such ends clamp or mold pieces I I' of heavy cross-section and conforming to the shape of the top and bottom faces of the rail are applied and held rigidly by means of yokes K and wedge-keys K' or other suitable 100 clamping appliances, the faces of said mold-pieces being in alinement with the body portions of the rails and bridging the joint between the rail ends. In practice the chocks L, preferably of wrought-iron and of a shape 105 to approximately fit the space between the flange and head of the rail, are applied to each side and preferably after having been heated to a welding heat. The press A A' is then brought into operation and the chocks 110 squeezed toward each other, causing the metal to flow into and through the openings in the rail ends and weld firmly together. The pressure applied causes the vertical spreading or a tendency of the rail ends to spread 115 vertically, and the heads of said ends are thereby brought up firmly against the under surface of the top mold-piece. The flanges are also seated firmly against the bottom mold-piece, and the whole joint is held under pressure until set in this position. In practice the metal of the chocks swells out 120 above and below the faces of the dies to a certain extent, forming top and bottom flanges which strengthen the joint to a very material 125 degree, and, furthermore, exert a positive upward and downward pressure on the rail-head and flange, respectively, which in addition to the lateral pressure on the web effects the desired result.

Where desired, the faces of the dies may be provided with slight projections, as indicated at m in Fig. 1, opposite the openings in the webs of the rails in order to insure an equali- 130

zation of the pressure at the point where a portion of the metal squeezes through said opening.

Obviously the particular form of apparatus employed is not essential; but it is highly desirable to have a press which will be capable of operation in a comparatively limited excavation around the adjacent rail ends in order to avoid so far as possible the necessity of tearing up the pavement or street-surface along the track, and such an apparatus as that illustrated has proven itself to be highly efficient. It is obvious also that any ordinary method of cleaning and fluxing the chocks may be employed, and, further, that while the process herein described is particularly useful where rails have been in use and the ends somewhat distorted, still, inasmuch as in practice it is found that new rails vary considerably, due to causes not necessary to mention herein, the process is highly advantageous in the laying of new tracks, inasmuch as it insures a proper alinement of the wheel-surface regardless of any slight variation in the size or shape of the rails to be united.

In this specification and claims where the term "pressure" is used we mean either continuous or uninterrupted pressure—*e. g.*, a gradual pressure, as from a hydraulic press, or blows, as from a hammer or the like.

Having thus described our invention, what we claim as new, and desire to secure by Letters Patent, is—

1. The herein-described improvement in the art of joining adjacent ends of railroad-rails, consisting in applying chocks thereto which are preliminarily heated to a welding heat and finally applying sufficient continued pressure to the outer opposite faces of the chocks to weld the same together and simultaneously raise the heads of the rails into surface alinement; substantially as described.

2. The herein-described improvements in the art of joining the adjacent ends of railroad-rails consisting in applying chocks thereto which are preliminarily heated to a welding heat, applying sufficient continued pressure to the outer opposite faces of the chocks to weld said chocks together and raise the head of the rails into surface alinement and restraining the vertical spreading of said rail ends at the point of surface alinement; substantially as described.

3. The herein-described improvement in the art of joining adjacent ends of railroad-rails consisting in applying a rigid mold to the rail-surface, applying chocks which are preliminarily heated to a welding heat to the opposite faces of the rail-webs and finally applying sufficient continued pressure to the opposite faces of the chocks to weld said chocks together and spread the rail ends into contact with the mold; substantially as described.

4. The herein-described method of joining adjacent ends of railroad-rails consisting in perforating the webs of the rails near their ends, applying chocks thereto which are preliminarily heated to a welding heat, applying sufficient continued pressure to the outer opposite faces of the chocks to weld the rail ends together through the perforations in the webs and spread said rail ends vertically and restraining the spreading action of said rail ends to form a true wheel-surface; substantially as described.

5. The alinement of rail ends, consisting in placing the adjacent rail ends in a top and bottom clamp shaped to the required alinement, and forming them into said clamp by pressure laterally applied to the said rail ends between the top and bottom of the clamp.

6. The alinement of rail ends, consisting in placing the adjacent rail ends in a top and bottom clamp shaped to the required alinement, heating said rail ends, and forming them into said clamp, by pressure applied to said ends between the top and bottom of the clamp.

7. The alinement of rail ends and the securing of the same, consisting in placing the adjacent rail ends in a clamp shaped to the required alinement, securing metal placed against said rail ends thereto, and forming said rail ends into said clamp.

8. The alinement of rail ends having apertures therein and the securing of the same together, consisting in placing the adjacent rail ends in a clamp shaped to the required alinement, securing metal placed against said rail ends together through said apertures, and forming said rail ends into said clamp by lateral pressure applied to said rail ends after the same have been heated.

9. The alinement of rail ends having apertures therein and the securing of the same together, consisting in placing the adjacent rail ends in a clamp shaped to the required alinement, welding heated metal chocks placed against said rail ends together through said apertures by pressure applied thereto and heating said rail ends by heat from the said heated metal chocks and the pressure applied thereto, and forming said heated rail ends into said clamp by pressure laterally applied.

10. The herein-described mode or method of joining adjacent ends of railroad-rails consisting in applying heated chocks thereto, and finally applying sufficient pressure to the outside surfaces of said chocks to cause them to adhere to said rails, and to spread the ends thereof vertically, substantially as described.
